UNITED STATES PATENT OFFICE.

CHESTER B. WINN, OF BUFFALO, NEW YORK

KNEE-JOINT FOR ARTIFICIAL LEGS.

1,115,361.

Specification of Letters Patent. Patented Oct. 27, 1914.

Application filed August 19, 1914. Serial No. 856,015.

To all whom it may concern:

Be it known that I, CHESTER B. WINN, of Buffalo, in the county of Erie and State of New York, have invented certain new and useful Improvements in Knee-Joints for Artificial Legs; and I do hereby declare that the following is a full, clear, and exact description thereof, which will enable others skilled in the art to which it appertains to make and use the same, reference being had to the accompanying drawings, and to the reference-numerals marked thereon, which form part of this specification.

The purpose of my present invention is to provide for artificial legs a knee joint of improved construction and operation and also to provide a joint which is simple and economical in construction and efficient and durable in operation.

A further purpose of my invention is to provide a knee joint construction composed of very few parts and having those few parts of simple formation and such as may be readily assembled or taken apart.

A further purpose of my invention is to provide a knee joint wherein the knee bolt or journal is supported upon the lower leg section at the middle of said bolt and also at both ends at the extreme outer sides or surfaces of the lower leg section whereby a knee joint is secured that is peculiarly well adapted to resist the strains to which the knee joint is subjected and whereby a sufficiently strong knee joint is obtained with a minimum of weight.

A further purpose of my invention is to provide a knee joint wherein the knee bolt extending through the knee of the thigh section of the leg is supported at both ends and at its middle upon the lower leg section and yet is secured to the lower leg section by a single fastening means whereby the knee joint is readily assembled or taken apart.

A still further purpose of my invention is to provide a knee joint wherein the T-bolt journaled in the knee portion of the thigh section of the leg has its ends rest in open-topped supports extending upwardly from the lower leg section on each side while the tail piece of the T-bolt is detachably secured to the lower leg section so that the knee joint of my invention has the readily detachable advantage of a knee joint wherein only the tail of the T-bolt is fastened to the lower leg section and also has the advantage of end supports for the T-bolt.

Another purpose of my invention is to provide improved means of operating the lower leg section upon its knee joint which means shall be simple and efficient and readily attached to or used in combination with a simple form of knee joint.

A still further purpose of my invention is to provide an improved knee joint and means of operating the same through upwardly extending straps whereby the desired power and movement is obtained and an unpleasant slipping of the shoulder straps or excessive movement thereof is avoided when the knee joint is bent.

Figure 1 is a side view of the lower end of the thigh section and the upper end of the lower leg section of an artificial leg embodying my invention. Fig. 2 is a rear view of the leg shown in Fig. 1. Fig. 3 is a perpendicular sectional view on line 3—3 of Fig. 2. Fig. 4 is a sectional view on line 4—4 of Fig. 1. Fig. 5 is a sectional view similar to Fig. 3, but with the knee joint bent and with the sections of the leg in the position they assume when the wearer is sitting down. Fig. 6 is a side view of the T-bolt and its pivotally connected curved link but with the near enlarged head of the journal piece of the bolt removed. Fig. 7 is a top view of the parts shown in Fig. 6 but with both heads upon the journal portion of the T-bolt.

Referring to the drawings in a more particular description there is shown the lower end of the usual hollow thigh portion 10 with its lower end curved or rounded to form the usual knee 11 and provided with a vertical central slot 12 at the rear extending from the lowest point of the knee to a point above the level of the knee bolt. The knee bolt 13 is journaled at both sides of its center in suitable bearings 14 extending transversely of the thigh section 10 and is provided at each end with enlarged heads 15, the inner surface 15^a of which above the bolt 13 bears against the adjacent outer surface of the thigh section so that while the knee bolt freely rotates in the thigh section movement of the bolt longitudinally of itself or transversely of the thigh section is prevented. From the middle of the knee bolt 13 projects a strong tail piece 16 which swings through the slot 12 in the knee 11 of the thigh portion and projects downwardly with its outer surface at the upper end of the lower leg section 17 where said tail piece has its end of reduced diameter forming a shoulder

18 resting upon the top of a bridge 19 extending transversely of the lower leg section while the lower end 16^a of said bolt projects through an aperture 20 in said bridge and is then screw-threaded receiving a nut 21 and preferably between the nut and the lower side of the bridge a metallic washer 22.

Upon the upper portion of both sides of the lower leg section 17 are provided upwardly extending projections 23 the upper ends of which form semi-circular open-topped supports 24 into which rests the lower side of the ends of the knee bolt 13 said knee bolt projecting outwardly from the opposite sides of the knee 11 of the thigh section 10. Against the outer sides of these side projections 23 at 23^a immediately below the open-topped supports 24 bear the inner surface 15^a of the bolt heads 15 whereby any movement of the lower leg section longitudinally of said knee bolt is prevented and most of the side strain is removed from the tail piece 16 of the T-bolt. These upward projections 23 may be formed integral with the lower leg section 17 but preferably will be formed of stronger and harder or heavier material than is necessary for the body of the lower leg section 17. Where as is commonly the case the main body of lower leg section 17 is formed of relatively light wood such as willow, the upward projections 23 may be formed of a piece of much harder and heavier wood such as hickory or ash let into the body of lower leg section 17 and securely fastened in position and properly supported as by resting down upon the ends of bridge 19 as plainly shown in the drawings. Adjusting screws 25 may be used in the usual manner to effect proper regulation and fit of the bearings 14 in the knee of the thigh piece about the knee bolt 13. These tightening screws 25 are shown in the drawings as being mounted in blocks 26 inserted in the diagonal slots 27 made in the rear of the knee 11 during the process of locating the T-bolt and its bearings permanently in the thigh section.

It will now be seen that with the two sections of the leg properly formed and with the T-bolt permanently journaled in the thigh section as indicated, the knee joint is assembled and the two sections of the leg pivotally secured to each other by simply bringing the two sections of the leg together with the projecting ends of the T-bolt resting in the supports 24 and with the shoulder 18 of tail piece 16 resting upon bridge 19 and the screw-threaded end 16^a of said tail piece projecting through the aperture 20 of said bridge below which bridge the said downwardly projecting end 16^a of said tail piece receives washer 22 and nut 21. The knee joint thus assembled may be very readily taken apart simply by removing nut 21

from downwardly projecting ends 16^a of the tail piece of the knee bolt and then drawing the thigh piece and its attached T-bolt directly away from the lower leg section 17.

It will now be seen that my invention provides a very simple knee joint which may be connected or disconnected by screwing into place or removing from its place one nut and that with this simplicity is combined the advantage of having the knee bolt supported at both ends and its middle upon the lower leg section which latter advantage has heretofore only been practically possible with knee bolts either permanently secured to the lower leg section or having separate attaching or fastening members. This combination of ready detachability of the knee joint with an end support or three-point support of the T-bolt upon the lower leg section is of great advantage in that it combines ease of manufacture, fitting, adjusting and repair of the leg with great strength and durability of the knee joint in actual use.

As a peculiarly simple and efficient means of operation of a knee joint wherein as heretofore described a knee-bolt permanently journaled in the thigh section has a downwardly projecting portion rigidly secured to the lower leg section, I provide upon the knee bolt 13 forwardly projecting arms 28 upon which as by pin 29 is pivotally mounted a link 30 which has its side 31 which is toward the rear when the link is swung upwardly relative to the tail piece 16 recessed or inwardly curved as plainly indicated in several figures of the drawings. To the outer end of link 30 which is preferably supplied with the roller 32 on pin 33 is rollingly mounted the looped lower central portion of a strap 34 the upwardly extending ends of which preferably pass over rollers 35 and 36 at the front and rear of the thigh section and thence outward through slots 37 and 38 in the front and rear respectively of the thigh section and are then secured in any desired way as to the ordinary shoulder straps (not shown), whereby the wearer of the limb by slight elevation of his shoulders puts a strong upward tension or pull upon the strap 34 in the way usual to shoulder-operated or controlled knee joints.

The arms 28 projecting forwardly from the knee bolt act in an obvious manner as crank arms transmitting a rotating motion to the knee bolt 13 in its bearings in the thigh portion and through the rigid connection of tail piece 16 to the lower leg section upward movement of said arms 28 moves the lower leg section forwardly upon the knee joint.

In knee joints controlled by a strap operatively connected to a crank arm upon the knee bolt as hereinbefore described it is necessary that the said crank arm project

substantially directly forward from the knee bolt relative to the lower leg section in order that sufficient leverage may be had for completing the forward movement of the lower leg in walking and particularly to enable the wearer with certainty to hold the leg in rigid extended position without conscious effort when standing. If now the control strap 34 were passed about the outer end of the crank arms of the knee bolt the extreme backward movement of the lower leg section relative to the thigh section as in kneeling or the extreme backward movement of the thigh section relative to the lower leg section as in sitting down would cause an excessive downward pull upon or downward movement of the control strap 34 and its attached suspenders which pressure or movement is uncomfortable and undesirable. By providing a rigid link pivotally connected to the crank arms and provided with a recess in its rear side I obtain just as much leverage upon the crank arms 28 for the latter part of the forward movement of a step or for the stand-position and at the same time obviate the excessive downward pull or movement of the control strap when the knee joint is fully bent. The size and relative construction of the link 30, arms 24 and knee bolt 14 are such that when the knee joint is fully bent as illustrated in Fig. 5 the link 30 swings to the rear with its recessed side fitting closely down upon the knee bolt 13 and allows the free end of the link over which is looped the strap 34 to pass considerably back of the knee bolt 13 or lets it pass to a position above the knee bolt relative to the thigh portion of the leg instead of keeping it in front of the knee bolt as would be the case were the strap secured directly to the crank arms 28. Furthermore this construction prevents the doubling up of the control strap 34 upon itself and prevents it being partially rolled up about knee bolt 13 as would be the case were it attached directly to the crank arms 28. It will be obvious from an inspection of the different drawings and particularly from Fig. 5 that as the curved link 30 gradually folds down about the knee bolt 13 the downward pull of control strap 34 or undesired movement of shoulder suspenders connected thereto decreases in reverse proportion to the extent of movement of said curved link 30. It will be obvious that a great range of relative proportion or arrangement of curved link 30 relative to the other parts may be made to obtain a greater or less extent of the advantage of this construction without departing from the spirit of my invention. It will be further noted that this method of controlling the knee joint by means of crank arms and a curved link is peculiarly efficient and convenient in connection with the knee joint

construction herein before described in that in this means the joint control is assembled entirely upon the thigh portion of the leg and assembled with the knee bolt so that assembling of the knee joint places the knee-operating means into fully operative position and removal of the knee bolt as hereinbefore described from its connection with the lower leg section at the same time removes the knee-operating mechanism from the lower leg section. In other words the knee-bolt and knee-joint operating means are readily assembled or taken apart at the same time and without extra operations.

The tail piece 16 of the knee bolt 13 by contact with cushion 39 in the forward lower end of central slot 12 of the knee 11 of the thigh portion 10 acts in the usual manner as a stop preventing further motion when the leg has been straightened out. The construction herein shown of having the two ends of the knee bolt as well as the lower end of the tail piece anchored in the lower leg section 17 strengthens the tail piece in its capacity as a stop in that it provides a support for the tail piece and knee-bolt both above and below the striking point thereof with the cushion and thereby obviates the usual side strain or wrenching strain that is present when only the lower end of the tail piece is secured to the lower leg section.

What I claim as new and desire to secure by Letters Patent is:

1. In a knee joint of an artificial leg the combination of a thigh section having a centrally disposed vertical slot in the rear of the knee, a T-bolt permanently journaled in the knee portion of the thigh section having its tail piece in said slot and the ends of the journal piece projecting beyond the knee, a lower leg section apertured at its top to receive the knee of the thigh section and provided with an upwardly extending projection on each side forming an open-topped support for said journal ends and means for supporting said tail piece upon and detachably securing it to the lower leg section.

2. In a knee joint of an artificial leg the combination of a thigh section having a centrally disposed vertical slot in the rear of the knee, a T-bolt permanently journaled in the knee portion of the thigh section having its tail piece in said slot and the ends of the journal piece projecting beyond the knee, a lower leg section apertured at its top to receive the knee of the thigh section and provided with an upwardly extending projection on each side forming an open-topped support for said journal ends, means for supporting said tail piece upon the lower leg section and screw-threaded means for detachably securing said tail piece to the lower leg section.

3. In a knee joint of an artificial leg the combination of a thigh section having a centrally disposed vertical slot in the rear of the knee, a T-bolt permanently journaled in the knee portion of the thigh section having its tail piece in said slot and the ends of the journal piece projecting beyond the knee, a lower leg section apertured at its top to receive the knee of the thigh section and provided with an upwardly extending projection on each side forming an open-topped support for said journal ends, a bridge in the lower leg section adapted to support the lower end of the tail piece of said bolt and means detachably securing said tail piece to said bridge.
4. In a knee joint of an artificial leg the combination of a thigh section having a centrally disposed vertical slot in the rear of the knee, a T-bolt permanently journaled in the knee portion of the thigh section having its tail piece in said slot and the ends of the journal piece projecting beyond the knee, a lower leg section apertured at its top to receive the knee of the thigh section and provided with an upwardly extending projection on each side forming an open-topped support for said journal ends, a bridge in the lower leg section adapted to support the lower end of the tail piece of said bolt and screw-threaded means detachably securing said tail piece to said bridge.
5. In a knee joint of an artificial leg the combination of a thigh section having a centrally disposed vertical slot in the rear of the knee, a T-bolt permanently journaled in the knee portion of the thigh section having its tail piece in said slot and the ends of the journal piece projecting beyond the knee, a lower leg section apertured at its top to receive the knee of the thigh section and provided with an upwardly extending projection on each side forming an open-topped support for said journal ends, means for supporting said tail piece upon and detachably securing it to the lower leg section and enlarged heads upon the projecting journal ends having their inner surface bear against the outside of the thigh portion above said journal whereby movement of said thigh section longitudinal of said journal is prevented.
6. In a knee joint of an artificial leg the combination of a thigh section having a centrally disposed vertical slot in the rear of the knee, a T-bolt permanently journaled in the knee portion of the thigh section having its tail piece in said slot and the ends of the journal piece projecting beyond the knee, a lower leg section apertured at its top to receive the knee of the thigh section and provided with an upwardly extending projection on each side forming an open-topped support for said journal ends, means for supporting said tail piece upon and detachably securing it to the lower leg section and enlarged heads upon the projecting journal ends having their inner surface bear against the outside of the thigh portion above said journal whereby movement of said thigh section longitudinal of said journal is prevented.
7. In a knee joint of an artificial leg the combination of a thigh section having a centrally disposed vertical slot in the rear of the knee, a T-bolt permanently journaled in the knee portion of the thigh section having its tail piece in said slot and the ends of the journal piece projecting beyond the knee, a lower leg section apertured at its top to receive the knee of the thigh section and provided with an upwardly extending projection on each side forming an open-topped support for said journal ends, means for supporting said tail piece upon and detachably securing it to the lower leg section, forwardly extending arms upon the knee journal and upwardly extending means operatively connected thereto whereby upward tension upon said means moves the lower leg section forwardly.
8. In a knee joint of an artificial leg the combination of a thigh section having a centrally disposed vertical slot in the rear of the knee, a T-bolt permanently journaled in the knee portion of the thigh section having its tail piece in said slot and the ends of the journal piece projecting beyond the knee, a lower leg section apertured at its top to receive the knee of the thigh section and provided with an upwardly extending projection on each side forming an open-topped support for said journal ends, means for supporting said tail piece upon and detachably securing it to the lower leg section, forwardly extending arms upon the knee journal, a link pivotally connected to the forward end of said arms and having its rear side recessed and adapted to fit over the knee journal as the joint is bent and an upwardly extending strap connected to the upper end of said link whereby upward tension of said strap moves the lower leg section forwardly.
9. In a knee joint of an artificial leg, the combination of a thigh section, a lower leg section, a knee bolt journaled in the knee portion of the thigh section and rigidly connected to the lower leg section, forwardly extending arms upon the knee bolt, a link pivotally connected to the forward end of said arms and having its rear side recessed and adapted to fit over the knee bolt as the joint is bent and an upwardly extending strap connected to the upper end of said link whereby upward tension of said strap moves the lower leg section forwardly.
10. In a knee joint of an artificial leg, the combination of a thigh section, a lower leg section, a knee bolt journaled in the knee

portion of the thigh section and rigidly connected to the lower leg section, forwardly extending arms upon the knee bolt, a link pivotally connected to the forward end of 5 said arms and having its rear side recessed and adapted to fit over the knee bolt as the joint is bent and a strap having its lower portion rollingly looped about the upper end of said link and its ends upwardly ex-

tended whereby upward tension on said loop 10 moves the lower leg section forwardly.

In witness whereof I have affixed my signature, in the presence of two witnesses, this 4th day of Aug. 1914.
